CLAIM

The ornamental design for a push-button water outlet valve, as shown and described.

DESCRIPTION

FIG. 1 is a front, left and bottom perspective view of a push-button water outlet valve showing our new design; FIG. 2 is a rear, right and bottom perspective view thereof; FIG. 3 is a front view thereof; FIG. 4 is a rear view thereof; FIG. 5 is a left side view thereof; FIG. 6 is a right side view thereof; FIG. 7 is a top plan view thereof; and, FIG. 8 is a bottom plan view thereof.

The broken lines in the figures illustrate portions of the push-button water outlet valve that form no part of the claimed design.
